AUTOMATIC PHONOGRAPH

Arthur L. Knox, Fort Wayne, Ind., assignor, by
mesne assignments, to Farnsworth Research
Corporation, a corporation of Indiana

Application May 10, 1943, Serial No. 486,301

17 Claims. (Cl. 274—10)

1

This invention relates generally to automatic phonograph apparatus and more particularly to automatic phonograph apparatus for successively and repeatedly reproducing each of a plurality of records and for also automatically reproducing both sides of each of a plurality of records.

Automatic phonograph apparatus of the type mentioned above, includes a magazine for supporting a stack of records adjacent the turntable together with a mechanism for releasing one record at a time from the magazine whereby each record is placed upon the turntable, one side is reproduced and the record is returned to the magazine. Reproduction of the other side of each record is accomplished by returning each record to the side of the magazine opposite to that from which the record was first removed. By providing apparatus for causing the magazine to rotate during each record-changing cycle, all records in the magazine may be reproduced on both sides. Automatic phonograph apparatus for accomplishing these results is not only noisy in operation but also includes complicated mechanisms for handling the records and controlling the record-changing cycle. Such mechanisms, because of their complication are difficult and expensive to manufacture. Delicate adjustments requiring excessive service in the field are also inherent in prior art mechanisms.

Accordingly, the principal object of this invention is to provide a novel record-changing apparatus of the type adapted continuously to reproduce each of the plurality of records and each side of those records.

Another object of this invention is to provide an automatic record-changing mechanism of such construction that noise in operation is reduced to a minimum.

In accordance with the present invention, there is provided an automatic phonograph apparatus for successively and repeatedly reproducing each side of each record of a plurality of records. The apparatus includes a pivoted magazine adapted to support a stack of records adjacent the phonograph turntable. The records are transferred from one side of the magazine to the turntable for reproduction by a pivoted and movable tray. After reproduction of the records, the magazine is rotated through an angle of 180° and the tray elevates the record from the turntable and deposits it in the rear portion of the magazine whereby the other side of the record will be reproduced when it is next transferred to the turntable. A simplified control mechanism for operating the magazine and the tray and controlling the record-changing cycle, includes a single cam gear having a plurality of cam surfaces for timing and accomplishing each control function of the mechanism whereby one record after another in the stack may be re-

2

produced. Furthermore, the control mechanism may be adjusted to provide continuous reproduction of the records for whatever period the listener desires.

5 For a better understanding of the invention, together with other and further objects thereof, reference is made to the following description taken in connection with the accompanying drawings, and its scope will be pointed out in the appended claims.

In the accompanying drawings:

Fig. 1 is a top plan view of the apparatus in accordance with the invention;

Fig. 2 is a side elevation, partly in section, showing a group of records in the magazine and a record on the turntable in playing position;

Fig. 3 is a bottom plan view of the apparatus of Fig. 1;

Fig. 4 is a top plan view of the record-changing mechanism taken on line 4—4 of Fig. 2 and rotated ninety degrees counterclockwise except that for purposes of clarity certain parts are omitted;

Fig. 5 is an enlarged fragmentary view, partly in section, showing the mechanism for controlling the positioning of the pickup arm over twelve-inch records;

Figs. 6 and 7 are fragmentary views, taken as indicated by lines 6—6 and 7—7 of Fig. 4, but showing the base plate and turntable and showing the mechanism for properly centering released records as they are moved into playing position upon the turntable;

Fig. 8 is a fragmentary view, taken on line 8—8 of Fig. 2, showing the means provided in the magazine for adapting the magazine for supporting a stack of ten-inch records or a stack of twelve-inch records;

Fig. 9 is a fragmentary view, taken from the direction shown by line 9—9 of Fig. 2, showing the mechanism for releasing a record from the magazine; and

Fig. 10 is a fragmentary view, taken from the direction shown by line 10—10 of Fig. 9, showing the position of the magazine, the record-moving members, and the record-releasing mechanism when a record is released from the magazine.

Referring now more particularly to Figs. 1—3 of the drawings, the invention here illustrated, embodies a phonograph apparatus including a base plate 15, and a rotatable shaft 16 supported thereby for operating a record-supporting turntable 17 and centering the records thereon. The turntable 17 and shaft 16 are driven by means of an electric motor 20, pulley 21, and friction wheel 22 which engages the inner surface of the flange at the edge of the turntable.

There is provided for reproducing the record 23 on the turntable, a pickup 25 having a stylus

26. The pickup is supported at one end of the pickup arm 27 which is pivoted at its opposite end on a tubular shaft 29 rotatable in a pedestal 30. The pedestal 30 may be fixed in any suitable manner to the base plate 15. For engaging pickup arm 27 and elevating the stylus 26, there is provided a pin 31 within the tubular shaft 29. This construction is illustrated in detail in the United States Patent of Arthur L. Knox and Fritz Kahl, 2,332,650, dated October 26, 1943.

As shown in Fig. 2, the turntable shaft 16 is tapered at its upper end to facilitate in centering a record as it is moved into playing position upon the turntable 17.

There is provided for supporting a stack of records 33 in a magazine at one side of the turntable 17 a shaft 35 rotatably supported by the base plate 15. Pinion gear 37 is affixed to its lower end in engagement with a rack 38 provided on a beam or connecting link 39 (Figs. 2-4). At the upper end of the shaft 35 there is affixed a magazine 40 for receiving conventional records of various diameters such as those having a diameter of approximately ten inches and those having a diameter of approximately twelve inches.

The magazine includes a ring 41 which is of a diameter slightly greater than that of a twelve-inch record. Affixed to the lower portion of the ring 41 is a pair of members 42 disposed to engage the lower edge portion of a stack of records to support the records in the magazine. The lower edge of the rear record of the stack is prevented from sliding out of the magazine by means of a flange portion 43 (Fig. 9) which extends above the inner surface of the ring 41.

For retaining twelve-inch records in the magazine there is provided a pair of ears 44 near the upper side of the ring 41 (Fig. 8) whereby the upper edge portion of the rear record of a stack of twelve-inch records will have its upper edge in engagement with the ears 44. Pivoted connected to the upper edge of the magazine 40 is a record-retaining member 46. A spring catch 47 is fixed to the member 46 (Figs. 2 and 8). As shown in Fig. 8, the member 46 is provided with a pair of ears 49 whereby, to play a stack of ten-inch records, the member 46 may be manually moved to the full-line position shown in Fig. 2, so that ears 49 are disposed to be engaged by the upper edge of the rear record of the stack of ten-inch records. When it is desired to reproduce twelve-inch records, the member 46 may be moved to the dotted-line position shown in Fig. 2 and spring catch 47 is engaged with the upper edge of the magazine 40.

For transferring records one at a time from the magazine 40 to the turntable 17 the rear record of the stack is separated from the stack by means of a spring-biased record-separating lever 50 (Figs. 1, 2 and 9). This lever is pivoted intermediate its ends as at 51 to a depending bracket 52 carried by the magazine whereby the right-hand end of the lever 50 extends into a slotted area 55 provided in the magazine 40 and is adapted to engage and lift the rear record above the flanged portion 43 (Fig. 9) to release the rear record from the magazine. The lever 50 is maintained in an inoperative position by means of a spring member 56 one end of which is connected to the magazine 40 and the other end of which is connected to the left-hand end of the lever 50. When the magazine 40 is rotated 180° in a counterclockwise direction, in a manner hereinafter to be described, the lever 50 is moved from the full-line to the dotted-line position shown in

Fig. 9, where it is actuated in a manner to be described hereinafter, to release a record from the magazine.

When a record is released from the magazine, 5 the next step is to move the record from the magazine to the turntable. For so moving the record, there is provided a pair of brackets 60 which extend above the base plate 15 (Fig. 1) to rotatably support a shaft 61. A lever 63 is connected to the left-hand end of the shaft 61 (Fig. 1) for operating record-separating lever 50. Secured to the right-hand end of the shaft 61 is a segmental gear 65, having teeth in mesh with a segmental driving gear 66 pivotally supported on 10 a pin 68 affixed to a bracket 69 depending below the base plate 15 (Fig. 2). Also, affixed to the shaft 61, between the brackets 60 are a pair of record-carrying members 70 which comprise a tray formed to be substantially concentric with the turntable 17. For centering twelve-inch records there are provided the stop pins 71 on members 70. The members 70 are adapted to be elevated to a position closely adjacent the magazine for receiving a record from the magazine when it 15 is in the dotted-line position shown in Fig. 2. Cushioning pads 73 are provided on the members 70 (Fig. 1) for silencing the drop of a released record. As the members 70 swing downwardly on shaft 61 the record rests on record-engaging portions 74 provided on the members 70. These portions 74 are covered with suitable soft material such as felt to prevent any marring of the playing surface of the record.

While the members 70 are lowering the released record toward the turntable, the record must be moved forward to properly position it so that the centering aperture of the record may be aligned with the centering pin 16 on the turntable 17. The mechanism for moving the record forward 20 on the members 70 is shown in Figs. 1, 4, 6 and 7. There is provided a pair of brackets 77, depending below the base plate 15, for pivotally supporting a shaft 78. Affixed thereto is a pair of record-centering members 81 and 82, which extend upwardly through a pair of slots 84 provided in the base plate 15, and is maintained in the position shown in Figs. 6 and 7 relative to the turntable 17, by means of a spring member 85 (Fig. 7). One end of the spring 85 is affixed to an adjustable screw 86 provided on the member 81, and its opposite end abuts the underside of the base plate 15 (Fig. 7). The mechanism for moving the members 81 and 82 includes a member 88 affixed to the shaft 78 (Figs. 4 and 6) and has a finger 89 25 provided with a notch 90 (Fig. 6). The member 88 is disposed to be engaged and actuated by a spring-biased lever 93 pivotally mounted as at 94 on the magazine-operating beam 39 (Fig. 4). The lever 93 is normally biased into engagement with 30 a stop pin 95, provided on the beam 39, by means of a spring 96 one end of which is connected to the lever 93 and the other end of which is connected to the beam 39 (Fig. 4). As shown in Fig. 4, the lever 93 is provided with a notched portion 97. When the beam 39 is moved downwardly (Fig. 4) in a manner presently to be described, the lever 93, which normally is in engagement with the stop pin 95, engages the finger 89 of the member 88 (Fig. 6) and moves the member 88 and members 81 and 82 (Figs. 4, 6 and 7) in a clockwise direction, thereby compressing the spring 85. When the lever 93 moves further downwardly and out of engagement with the finger 89, the members 81, 82 and 88 are returned to their normal position, shown in Figs. 6 and 7, by the spring 35

85. When the beam 39 is moved upwardly, the notched portion 97 of the lever 93 engages the notch 90 of the member 89. As the beam 39 continues to move upwardly, the lever 93, under the influence of the spring 96, moves the members 81, 82 and 89 in a counterclockwise direction, from the position shown in Figs. 6 and 7 whereby the notch-positions 81A and 82A (Figs. 6 and 7) engage the lower peripheral edge of the record on the record-moving members 70, as shown in broken-lines in Fig. 2 and slide the record forwardly on the members 70. The lever 93 normally moves the members 81 and 82 in a counterclockwise direction sufficiently far to position a ten-inch record on the members 70 so that its centering aperture will engage the centering pin 16 when lowered onto the turntable 17. When a twelve-inch record is resting on the members 70, the members 81 and 82 engage and move the record forwardly until its peripheral edge engages the stop pins 71 on the members 70, thereby to position the record to engage the centering pin 16. However, the record engages the stop pins 71 before the lever 93 moves out of engagement with the member 88 (Fig. 4). Thus, the member 88 cannot move further in a counterclockwise direction (Fig. 6). Consequently, the lever 93 is permitted to move in a clockwise direction (Fig. 4) against the biasing action of spring 96 until its notched end 97 moves out of engagement with the notch 90 of the member 88 (Fig. 6). Thus, the escapement provided by spring 96 makes possible the centering of both ten-inch and twelve-inch records by a single centering mechanism.

The mechanism for carrying out a record-changing cycle, is disclosed in Figs. 2-4, and includes a pinion gear 100 on the turntable shaft 16 together with a mutilated cam gear 101 driven thereby and mounted on a shaft 102 (Fig. 2). The cam gear is shown in its complete form in Figs. 3 and 4, the lower surface being shown in Fig. 3 and the upper surface being shown in Fig. 4. The cam gear 101 has several teeth removed as at 103, the purpose of the mutilation being to break the driving connection with the pinion gear 100. Thus, complete revolution of the cam gear 101 defines a complete record-changing cycle, as will be evident hereinafter.

The cam gear is provided with a pickup arm 27 controlling cam surface 105, as shown in Figs. 2, 3 and 4. The cam surface 105 is provided with a notched or recessed portion 105A. The pin 31, which is movable in the tubular shaft 29 (Fig. 2) normally engages the recessed portion 105A when the cam gear is at rest. As the pin 31 follows the cam surface 105, it moves up and down to impart vertical movement to the pickup arm 27.

As shown in Figs. 2 and 4, a lever 108 is affixed to the lower end of the tubular shaft 29 and to its upper end there is fixed the pickup arm 27. Horizontal movement of the lever 108 effects a corresponding movement of the pickup arm 27 and vice versa. To the other end of the lever 108 is fixed a pin 109 which moves within an elongated aperture 110 provided in an arm 112 (Fig. 4) of a U-shaped lever 113 (Figs. 2-4). Lever 113 is pivoted on a stud 114, on the under side of the base plate 15 (Fig. 2). This lever is provided with a second arm 116 to which is affixed a pin 117, arranged to track the cam groove 106 (Fig. 3).

The aperture 110 is large enough so that the pin 109 may move freely over a wide arc corresponding to the movement of the pickup arm 27 during the reproduction of a record. The pin 117 on the arm 116 engages the cam surface 107 of

groove 106 (Fig. 3) and is maintained in contact with the cam surface 107 by a spring 120, one end of which is connected to the arm 116 and the other end of which is connected to an arm 121, fixed to the shaft 102 (Fig. 3). After the stylus 26 has been raised from the surface of the record on the turntable 17, in the manner previously described, and as the cam gear 101 continues to rotate, the cam surface 107 moves the arm 116 of the U-shaped lever 113 in a counterclockwise direction (Fig. 3) about its pivot 114 thereby moving the arm 112 in a clockwise direction (Fig. 4) causing the left-hand side of the aperture 110 to engage and drive before it the pin 109. Thus, the pin 109 and the lever 108 move the pickup arm 27 in a radial direction away from the center of the record. The cam surface 107 is so shaped that when the pickup arm reaches a predetermined distance beyond the edge of the record on the turntable, the pin 117 enters the concentric portion of cam groove 106 and the arm 112 ceases its clockwise rotation.

For moving the record-moving members 70 (Fig. 1) from the full-line position shown in Fig. 2 to a first plane for depositing a record in the magazine 40 and to a second plane for receiving a record from the magazine 40, there is provided a link or beam 123 (Fig. 3) having an elongated aperture 124 which permits the beam to move with respect to shaft 102 (Fig. 3). The upper end of the beam is pivotally connected, as at 125, to the segmental gear 66 which is operatively associated with the segmental gear 65 (Figs. 1 and 2). The beam 123 is adapted to be moved by a pin 126 affixed thereto for tracking the cam groove 127 provided in the lower surface of the cam gear 101 (Fig. 3). Groove 127 is formed to impart several different motions to tray 70 as will be explained hereinafter. A spring member 128, which is connected between the base plate 15 and a rod 129 slidably connected to the segmental gear 66 (Fig. 2), assists in moving the segmental gears 65 and 66 and the members 70, as will presently be described.

As shown in Fig. 3, a lever 130 is pivotally mounted as at 131 on the lower end of the beam 123. To the free end of the lever 130 there is connected a roller 132 which engages a notch 133 provided in the cam gear 101 (Fig. 3), and is maintained in contact with the notch 133 by a spring 135, which is connected between the lever 130 and the beam 123. Engagement of the roller 132 with the notch 133 maintains the cam gear 101 in a neutral position during a record-reproducing period.

The mechanism for moving the magazine 40 between its record-receiving and record-releasing positions in timed relation with the movement of the members 70 includes the beam 39 (Fig. 4), which is provided with an elongated aperture 138 whereby to allow movement with respect to the shaft 35 of the magazine 40. The lower end of the beam 39 is provided with an elongated aperture 139 whereby to allow movement over a collar 140 on the shaft 102 (Fig. 4). The beam 39 is moved by a pin 141 affixed thereto which tracks a cam groove 143 provided in the upper surface of the cam gear 101 (Fig. 4). Groove 143 is formed to provide movement of the magazine 40 as will be described hereinafter.

The automatic record-changing cycle effected by a complete revolution of the cam gear 101 is initiated by an automatic tripping mechanism. In moving toward the center of the record during the playing thereof, the pickup arm 27 moves with

it the tubular shaft 29 which has secured to it a clutch 145 (Fig. 2). Clutch 145 comprises a flanged sleeve 146, affixed to the tubular shaft 29, and a friction washer 147 upon the upper surface of the annular end of the lever 108, also affixed to the tubular shaft 29. The annular end of a lever 148 (Fig. 4) is interposed between the friction washer 147 and the flanged sleeve 146 for rotation about the tubular shaft 29. Thus, as the pickup arm 27 moves toward the center of the record, the frictional contact between the lever 148, the sleeve 146, washer 147 and lever 108, moves the lever 148 in a clockwise direction (Fig. 4). A turned-down end 150 provided on the lever 148 (Figs. 2 and 4) is adapted to engage a turned-up end 152 on a starting lever 153, which is pivotally mounted, intermediate its ends, by means of a screw 154 to the upper surface of the cam gear 101 (Fig. 4).

As the pickup arm 27 approaches the inner groove of a record, it moves the lever 148 in a clockwise direction, and the starting lever 153 in a counterclockwise direction (Fig. 4). With each clockwise revolution of the pinion gear 100 (Fig. 4), a cam 156, which is fixedly secured to the shaft 16, reverses the counterclockwise movement of the lever 153 by striking the front surface of the end 157 of the lever 153 (Fig. 4) thereby returning the levers 153 and 148 to their starting position. When the stylus 26 moves into the eccentric or spiral lead-in groove customarily provided as the innermost groove of a record, the lever 148 is moved rapidly in a clockwise direction, and the starting lever 153 is moved rapidly in a counterclockwise direction. Therefore, before the pinion gear 100 can complete a full revolution, the end 157 of the lever 153 moves into a position where the cam 156 engages the side of the end 157 of the lever 153 (Fig. 4). When this occurs, the opposite end of the lever 153 engages a stop 160 provided on the upper surface of the cam gear 101 (Fig. 4). As the cam 156 continues to rotate it moves the lever 153 and therewith the cam gear 101 in a counterclockwise direction (Fig. 4) sufficiently far so that its teeth mesh with the teeth of the pinion gear 100. Thereafter, the pinion gear 100 drives the cam gear 101 through a complete revolution to effect an automatic record-changing cycle. As the cam gear 101 rotates through a cycle, the end 157 of the lever 153 (Fig. 4) engages a small spring member 162 fixed to the stud 114 (Fig. 2), and is moved out of the position where the end 157 would be engaged by the cam member 156, thereby to prevent a second revolution of the cam gear 101 until the mechanism is automatically tripped for the next record-changing cycle.

In reproducing twelve-inch records, it is necessary to reduce the inward travel of the pickup arm 27. This is accomplished by a mechanism which intercepts the movement of the arm 112 (Fig. 4) as it moves the arm 108 and the pickup arm 27 inwardly. This mechanism is disclosed in Figs. 2 and 5, and includes a member 165 which is positioned so that its upper end will be engaged only by a twelve-inch record when it is in playing position upon the turntable. As shown in Fig. 5 the member 165 is adapted to be moved vertically in a bracket 166 fixed to the under side of the base plate 15. The member 165 is provided with a pair of recessed portions 168 and 169 and a notched portion 170 (Fig. 5). Portions 168 and 169 are adapted to be engaged by a spring-biased ball 172, and the notch 170 is engaged by an adjustable screw 173, supported by an ear 174 pro-

vided on the arm 112 (Figs. 4 and 5). When the ball 172 engages with the recessed portion 168, the member 165 is maintained in the position shown in Fig. 5, its upper end extending above the upper surface of the turntable 17. When a ten-inch record is placed upon the turntable 17 and the arm 112 of lever 113 moves the pickup arm 27 inwardly, the notch 170 is adjacent the screw 173 (Fig. 5), and permits the arm 112 to move inwardly to its normal position, thereby to position the pickup arm over the initial playing groove of the record. However, when a twelve-inch record is placed upon the turntable 17, the record will engage the upper end of the member 165 and move it downwardly (Fig. 5). This causes the recessed portion 169 to move into engagement with the spring-biased ball 172 and the notched portion 170 to move out of the path of the screw 173 on the arm 112. With the member 165 in this latter position, the screw 173 engages the side of the member 165 to prevent arm 112 of the U-shaped lever 113 from moving as far in a counterclockwise direction as it otherwise would, whereby the pickup arm 27 is swung inwardly through a shorter arc than is the case when a ten-inch record is on the turntable 17. During the succeeding cycle, a cam member 178 provided on the upper surface of the cam gear 101 (Figs. 4 and 5) engages the lower end of the member 165 and moves it vertically from the dotted-line position to the full-line position (Fig. 5). If a ten-inch record is subsequently placed upon the turntable, the arm 112 is permitted to swing the pickup arm 27 inwardly over the initial groove. Thus, it is evident that the mechanism is adapted automatically to position the pickup arm so that the stylus engages the initial groove of the record regardless of whether it is a ten-inch record or a twelve-inch record.

Mode of operation

For purposes of illustration, it will be assumed that the member 46 of the magazine is adjusted to receive a stack of ten-inch records. It will also be assumed that a record has been placed in playing position on the turntable and a stack of ten-inch records has been placed in the magazine (Fig. 2). The pickup arm 27 may be moved manually to place the stylus 26 in the starting groove of the record on the turntable 17.

The pickup arm 27 moves inwardly as the stylus 26 tracks the playing groove of the record and eventually reaches the change groove, at which time the levers 148 and 153 (Fig. 4) move rapidly in response to the rapid movement of the pickup arm 27, whereby the lever 148 moves the lever 153 into the path of the cam 156 on the turntable shaft 16.

Engagement of the cam 156 with the end 157 of the lever 153 causes the cam gear 101 to rotate into mesh with the pinion gear 100. Cam gear 101 is driven by the pinion gear 100 through one revolution to control a record-changing cycle.

As the cam gear 101 rotates, the cam surface 105 (Figs. 2 and 4) moves the pin 31 vertically upward to lift the pickup arm 27 off the record and maintains it in an elevated position. Continued movement of the cam gear causes the cam surface 107 (Fig. 3) to move the arm 116 of the U-shaped lever 113 in a counterclockwise direction and the arm 112 in a clockwise direction (Fig. 4) whereby the left-hand side of the aperture 110 engages the pin 109 and moves the arm 108 in a counterclockwise direction to swing the pickup

arm 27 beyond the edge of the record on the turntable.

While the pickup arm is being swung to its outermost position, the pin 126 on the beam 123 is tracking the cam groove area 127A. Shortly after the pickup arm 27 is moved to its outermost position, the pin 126 tracks area 127B to move the beam 123 (Figs. 2 and 3) to the left and rotate the segmental gear 66 in a counterclockwise direction (Fig. 2). The segmental gear 66 rotates the segmental gear 65 and tray members 70 (Figs. 1 and 2) in a clockwise direction (Fig. 2) from the full-line to the vertical dotted-line position, to deposit the record in the magazine. Spring 128 exerts tension on gear 66 through enough of its rotation to lift the members 70 and the record almost to a vertical position whereby cam gear 101 is relieved from carrying the entire load. Immediately after the record is deposited in the magazine 40, the pin 126 tracks cam portion 127C to move the tray members 70 back to a position intermediate the full-line position and the vertical dotted-line position shown in Fig. 2, whereby to permit rotation of the magazine.

Shortly thereafter, the cam gear 101 rotates to a position where pin 141 in beam 39 tracks the cam groove area 143A of the cam groove 143 (Fig. 4) and moves the beam 39 downwardly (Figs. 3 and 4). This movement of the beam 39 causes the rack 38 affixed thereto to rotate the gear 37 in a clockwise direction (Fig. 3). As the gear 37 rotates, the magazine 40 is rotated in a counterclockwise direction (Fig. 1) from the full-line position to the dotted-line position shown in Fig. 2. While the magazine 40 is in its latter position, the pin 141 tracks the cam groove area 143B. Simultaneously, the pin 126 tracks cam groove area 127D to move the members 70 in a clockwise direction to the position shown in Fig. 10. The lever 63 movable with tray members 70, engages and elevates the free end of the record-releasing lever 50 (Figs. 9 and 10) to release a record onto the members 70, as shown in Fig. 2. Immediately thereafter, the pin 126 tracks the cam groove area 127E to move the beam 123 to the right (Fig. 2) and rotate the segmental gear 66 in a clockwise direction against the biasing action of the spring 128, thereby to rotate the segmental gear 65 and members 70 in a counterclockwise direction and lower the released record toward the turntable 17.

While the members 70 are being lowered, the pin 141 tracks the cam groove area 143C to move the beam 39 upwardly (Figs. 3 and 4). Thereupon the rack 38 rotates the gear 37 in a counterclockwise direction (Fig. 3) and the magazine 40 in a clockwise direction (Fig. 1) from the dotted line position back to the full-line position shown in Fig. 2.

As the beam 39 moves upwardly, the spring-biased lever 93 on the beam 39 (Fig. 4) engages the member 89 on the shaft 78 (Figs. 4 and 6) to move the members 89, 81 and 82 in a counterclockwise direction (Figs. 6 and 7). Meanwhile, because of the configuration of cam area 127E, tray members 70 are lowered to the position indicated in dotted lines just above the turntable as shown in Fig. 2. The tray is held in this position for an interval sufficient for the notched portions 81A and 82A to move into engagement with the lower peripheral edge of the record as indicated in broken lines in Fig. 2, and slide the record forward on the members 70. Thus, the record is substantially horizontal at the time during which it is centered. When the lever 93 moves beyond and out of engagement with member 89, the released rec-

ord is properly positioned or centered upon the members 70 for lowering it into engagement with the centering pin 16. As the cam gear continues to rotate, the pin 126 again tracks cam groove area 127A and the tray members 70 lower the record onto the turntable 17.

After the record is lowered onto the turntable, the cam gear 101 rotates to the position shown in Fig. 3, where the contour of the cam surface 107 permits the spring 120 to move the arm 116 in a clockwise direction (Fig. 3) and therewith the arm 112 in a counterclockwise direction (Fig. 4). When this occurs, the right-hand edge of the aperture 110 (Fig. 4) engages the pin 109, and moves the lever 108 and the pickup arm 27 to a position where the stylus 26 is over the initial groove of the new record.

The cam gear 101 rotates to the position shown in Figs. 2 and 4, where the contour of the cam surface 105 (Fig. 2) permits the pin 31 to move vertically downward and thereby return the stylus 26 into engagement with the new record on the turntable 17. Immediately thereafter, the mutilated portion of the cam gear 101 moves opposite gear 100 whereby the cam gear comes to rest in the position shown in Figs. 3 and 4 of the drawings, and reproduction of the record just placed upon the turntable takes place.

The next and following cycles of automatic operation are initiated by the automatic trip mechanism each time the stylus 26 moves into the trip groove of the record. The stack of records placed in the magazine 40 will be played continuously until the mechanism is manually shut off.

In the case of twelve-inch records, the record retaining member 46 is moved manually to the dotted line position to engage spring catch 47 with the outer frame of the magazine 40, as illustrated in Fig. 2. The stack of twelve-inch records may then be placed in position in the magazine to engage the retaining members 44 whereby the stack rests in position to have records removed therefrom.

The operation of the automatic record changer mechanism is the same in the case of twelve-inch records as in the case of ten-inch records except that the twelve-inch records are centered on the tray members 70 by means of the lugs 71. The record is moved forward, by the members 81 and 82, into engagement with the lugs 71 at which time the record-moving members come to rest by reason of the escapement mechanism. This mechanism comprises the pivoted lever 93 and the spring 96, the operation of which was described previously.

After the record has been placed on the turntable, the tone arm 27 is positioned for engagement of the stylus 26 with the initial playing groove of the record by reason of the provision of member 165. This member is forced downwardly by a twelve-inch record to such a position that notch 169 engages the spring pressed ball 172 and notch 170 is out of alignment with the pin 173. Thus, as explained hereinbefore, the tone arm control lever 113 can move to position the tone arm until the pin 173 engages the member 165 at which time the stylus 26 is over the initial playing groove of the record.

From the previous description, it will be obvious that this invention provides an automatic phonograph mechanism adapted continuously to reproduce each record in a stack of records and to reproduce both sides of each record. The arrangement of parts is such that the control mechanism

comprises a minimum number of parts which are operable without imposing undue mechanical stresses and strains on any individual part. The record-handling mechanism is peculiarly adapted to handle records in a gentle manner and accurately to center records over the turntable spindle. By reason of this, each individual record is handled without danger of mutilation.

While there has been described what is at present considered the preferred embodiment of the invention, it will be obvious to those skilled in the art that various changes and modifications may be made therein without departing from the invention, and it is, therefore, aimed in the appended claims to cover all such changes and modifications as fall within the true spirit and scope of the invention.

What is claimed is:

1. An automatic phonograph comprising a rotatable turntable for supporting a record, a movable magazine positioned in one plane adjacent said turntable for supporting a stack of records, driving means operatively associated with said magazine for moving it to a first position for receiving a record and to a second position for releasing a record, a movable record support positioned in another plane adjacent said turntable and said magazine, and means connected to said driving means and said record support for moving said record support in timed relation with respect to said magazine whereby, during a record-changing cycle when said magazine is in said second position, said record support may be moved to receive a record from said magazine and transfer it to the turntable, and said record support may be moved to transfer a record from the turntable to said magazine when said magazine is in said first position.

2. An automatic phonograph comprising a rotatable turntable for supporting a record, a movable magazine positioned adjacent said turntable and tilted from the vertical plane for supporting a stack of records, driving means operatively associated with said magazine for moving it to a first position for receiving a record and to a second position for releasing a record, a movable record-supporting device pivoted in a horizontal plane adjacent said turntable and said magazine, and means connected to said driving means and said record-supporting device for moving said device in timed relation with respect to said magazine when said magazine is in the record-receiving position or in the record-releasing position.

3. An automatic phonograph comprising a rotatable turntable for supporting a record, a movable magazine positioned in one plane adjacent said turntable for supporting a stack of records, means operatively associated with said magazine for rotating it, means connected to said means for moving said magazine to a first position for receiving a record and to a second position for releasing a record, a movable record-supporting device positioned in another plane adjacent said turntable and said magazine, and means connected to said second means and said record-supporting device for moving said device in timed relation with respect to said magazine whereby, during a record-changing cycle when said magazine is in said second position, said device may be moved to receive a record from said magazine and transfer it to the turntable, and said device may be moved to transfer a record from the turntable to said magazine when said magazine is in said first position.

4. An automatic phonograph comprising a rotatable turntable for supporting a record, a rotatable magazine positioned in one plane adjacent said turntable for supporting a stack of records, rack and pinion means operatively associated with said magazine for rotating it, cam means connected to said rack and pinion means for moving said magazine to a first position for receiving a record and to a second position for releasing a record, a movable record-supporting tray positioned in another plane adjacent said turntable and said magazine, and means connected to said cam means and said record-supporting tray for moving said tray in timed relation with respect to said magazine whereby, during a record-changing cycle when said magazine is in said first position said tray may be moved to transfer a record from said turntable to the magazine, and said tray may be moved to transfer a record from the magazine to said turntable when said magazine is in said second position.

5. An automatic phonograph comprising a rotatable turntable for supporting a record, a magazine positioned in one plane adjacent said turntable for supporting a stack of records, a record-releasing means adjacent said magazine for releasing a record from the stack, a record-supporting device positioned in another plane adjacent said turntable and said magazine and movable to a position parallel to said magazine for receiving a record from said magazine, driving means connected to said record-supporting device for moving said device, and means operatively associated with said driving means for operating said record-releasing means when said device is in record-receiving position.

6. An automatic phonograph comprising a rotatable turntable for supporting a record, a movable magazine positioned adjacent said turntable for supporting a stack of records, a movable record release lever pivoted on said magazine for engaging and releasing an outside record in said stack, a record-supporting device adjacent said turntable and said magazine and movable to and from said magazine for moving records between said turntable and said magazine, means connected to said record-supporting device for moving it between said magazine and said turntable, and means fixed to said device in position to move said lever on said magazine when said device is moved to said magazine.

7. An automatic phonograph comprising a rotatable turntable for supporting a record, a rotatable magazine positioned adjacent said turntable for supporting a stack of records, said magazine being movable during a record-changing cycle to a first position for receiving a record and to a second position for releasing a record, means operatively associated with said magazine for rotating it to said positions, a record release means on said magazine for releasing a record adjacent the turntable, a record-supporting device adjacent said turntable and said magazine and movable for moving records between said turntable and said magazine, driving means connected to said record-supporting device for moving said device in timed relation to movement of said magazine whereby said device may be moved to receive a record when the magazine is in said second position and transfer said record to the turntable, and said device may be moved to transfer a record from the turntable to said magazine when said magazine is in said first position, and means connected to said driving means for oper-

ating said record release means when said device is in position to receive a record.

8. In an automatic phonograph comprising a rotatable turntable for supporting a record, a magazine positioned adjacent said turntable for supporting a stack of records and movable to a first position for receiving a record and to a second position for releasing a record, means operatively associated with said magazine for moving said magazine to said first and second positions, a record-supporting tray adjacent the periphery of said turntable and movable for moving a record from said turntable to said magazine when said magazine is in said first position and movable for receiving a record from said magazine and moving it to said turntable when said magazine is in said second position, means operatively associated with said tray and said magazine moving means for moving said record-supporting tray in timed relation with the movement of said magazine to a position adjacent said magazine when it is in either of said positions, and means operatively associated with said tray and said magazine for releasing a record from said magazine to said tray when said magazine is in said second position and when said tray is adjacent said magazine.

9. In an automatic phonograph comprising a rotatable turntable for supporting a record, a pickup arm for reproducing a record on said turntable, a movable magazine positioned beyond the periphery of said turntable for supporting a stack of ten-inch records or a stack of twelve-inch records, a driving means, means operatively associated with said driving means and said pickup arm for elevating said pickup arm out of engagement with a record and moving it to the beginning of a record during a record-changing cycle, a first linkage operatively associated with said magazine and said driving means for moving said magazine to a record-receiving position or to a record-releasing position, a record-supporting tray pivotally mounted adjacent the periphery of said turntable, a second linkage operatively associated with said record-supporting tray and said driving means for moving said tray in timed relation with the movement of said magazine to a position adjacent the magazine when it is in the record-receiving or record-releasing position, a record-releasing means operatively associated with said magazine and said tray for releasing a record from said magazine to said tray when said magazine is in said record-releasing position, a pair of record-moving members pivotally mounted beyond the periphery of said turntable and adapted to engage the peripheral edge of a record on said tray and move said record on said tray as said tray moves said record toward said turntable to center said record with respect to said turntable, means on said tray for limiting the forward movement of a twelve-inch record, and means connected to said first linkage for actuating said record-moving members.

10. In an automatic phonograph comprising a rotatable turntable for supporting a record, a movable magazine positioned beyond the periphery of said turntable for supporting a stack of records, a driving means, a first linkage operatively associated with said magazine and said driving means for moving said magazine to a record-receiving position or to a record-releasing position, a record-supporting device movably mounted adjacent the periphery of said turntable, a second linkage operatively associated with said record-supporting device and said driving means

for moving said device in timed relation with the movement of said magazine to a position adjacent the magazine when it is in the record-receiving or record-releasing position, a record-releasing means operatively associated with said magazine and said device for releasing a record from said magazine to said device when said magazine is in said record-releasing position, a pair of record-moving members pivotally mounted beyond the periphery of said turntable and adapted to engage the peripheral edge of a record on said device and move said record on said device as said device moves said record toward said turntable to center said record with respect to said turntable, and means connected to said first linkage for actuating said record-moving members.

11. In an automatic phonograph comprising a rotatable turntable for supporting a record, a magazine positioned beyond the periphery of said turntable for supporting a stack of records, a driving means, a record-supporting device movably mounted adjacent the periphery of said turntable, a linkage operatively associated with said record-supporting device and said driving means for moving said device to a position adjacent the magazine, a record-releasing means operatively associated with said magazine for releasing a record from said magazine to said device, a record-moving member movably mounted beyond the periphery of said turntable and adapted to engage the peripheral edge of a record on said device and move said record on said device as said device moves said record toward said turntable to center said record with respect to said turntable, and means connected to said driving means for actuating said record-moving member.

12. In an automatic phonograph comprising a rotatable turntable for supporting a record, a magazine positioned beyond the periphery of said turntable for supporting a stack of ten-inch records or a stack of twelve-inch records, a driving means, a record-supporting device pivotally mounted adjacent the periphery of said turntable, a linkage operatively associated with said record-supporting device and said driving means for moving said device to a position adjacent the magazine, a record-releasing means operatively associated with said magazine and said device for releasing a record from said magazine to said device when it is adjacent the magazine, a record-moving member movably mounted beyond the periphery of said turntable and adapted to engage the peripheral edge of a record on said device and move said record on said device as said device moves said record toward said turntable to center said record with respect to said turntable, means on said device for limiting the forward movement of a twelve-inch record, and a spring-biased lever connected to said driving means and engaging said record-moving member for actuating it.

13. In an automatic phonograph comprising a rotatable turntable for supporting a record, a magazine positioned beyond the periphery of said turntable for supporting a stack of ten-inch records or a stack of twelve-inch records, a driving means, a record-supporting device pivotally mounted adjacent the periphery of said turntable, a linkage operatively associated with said record-supporting device and said driving means for moving said device to a position adjacent the magazine, a record-releasing means operatively associated with said magazine for releasing a record from said magazine to said device when

it is adjacent the magazine, a record-moving member movably mounted beyond the periphery of said turntable and adapted to engage the peripheral edge of a record on said device and move said record on said device as it moves said record toward said turntable to center said record with respect to said turntable, means on said device for limiting the movement of a twelve-inch record, and escapement means connected to said driving means and engaging said record-moving member for actuating it to center a ten-inch record or move a twelve-inch record to the limit allowed by said limiting means.

14. In an automatic phonograph comprising a rotatable turntable for supporting a record, a magazine movably mounted beyond the periphery of said turntable for supporting a stack of large or small records, a driving means, a first linkage connected to said magazine and said driving means for moving said magazine to a record-receiving position or a record-releasing position, a record-supporting member movably mounted beyond the periphery of said turntable, means on said record-supporting member for limiting the movement of large records, a second linkage operatively connected to said driving means and said record-supporting member for moving it in timed relation with the movement of said magazine to a record-depositing or receiving position adjacent said magazine when it is in either the record-receiving or record-releasing position, a record-moving member movably mounted beyond the periphery of said turntable and adjacent said record-supporting member, and spring-biased means connected to said first linkage to engage said record-moving member in timed relation with the movement of said record-supporting member for centering a small record with respect to said turntable or moving a large record into engagement with said limiting means.

15. In an automatic phonograph comprising a rotatable turntable for supporting a record, a pickup arm for reproducing a record on said turntable, means positioned adjacent said turntable for supporting a stack of ten-inch records or a stack of twelve-inch records, means adjacent said supporting means and said turntable for transferring records from the magazine to the turntable, driving means connected to said record-transferring means for operating it, a control lever operatively associated with said driving means and said pickup arm for moving said pickup arm beyond the edge of a record on said turntable and for returning said pickup arm to the beginning of a record on said turntable, and an intercepting means comprising a depressable notched member projecting into the plane of a twelve-inch record when said record is in playing position upon said turntable and disposed with respect to said control lever so that the control lever may enter the notch in said notched member when a ten-inch record is on said turntable but cannot enter said notch when the notch member is depressed by a twelve-inch record whereby to intercept the inward movement of said pickup arm moving means to properly position the pickup arm at the beginning of a twelve-inch record.

16. In an automatic phonograph comprising a rotatable turntable for supporting a record, a pickup arm for reproducing a record on said turntable, means positioned adjacent said turntable for supporting a stack of ten-inch records

or a stack of twelve-inch records, means adjacent said supporting means and said turntable for transferring records from the magazine to the turntable, driving means connected to said

5 record-transferring means for operating it, a control lever and cam operatively associated with said driving means and said pickup arm for elevating and moving said pickup arm beyond the edge of a record on said turntable and for returning said pickup arm to the beginning of a record on said turntable, an adjustable element on said lever, and an intercepting means comprising a notched member projecting into the plane of a twelve-inch record when said record is in playing position upon said turntable and disposed with respect to said adjustable element so that it may enter the notch in said notched member when a ten-inch record is on said turntable but cannot enter said notch when the notched member is depressed by a twelve-inch record whereby to intercept the inward movement of said pickup arm moving means to properly position the pickup arm at the beginning of a twelve-inch record.

25 17. In an automatic phonograph comprising a rotatable turntable for supporting a record, a pickup arm for reproducing a record on said turntable, means including a frame positioned adjacent said turntable, a movable member in said frame for supporting a stack of ten-inch records and projections on said frame for supporting a stack of twelve-inch records, means adjacent said supporting means and said turntable for transferring records from the magazine to the turntable, driving means connected to said record-transferring means for operating it, a control lever operatively associated with said driving means and said pickup arm for moving said pickup arm beyond the edge of a record on said turntable and for returning said pickup arm to the beginning of a record on said turntable, and an intercepting means comprising a notched member projecting into the plane of a twelve-inch record when said record is in playing position upon said turntable and disposed with respect to said control lever so that the control lever may enter the notch in said notched member when a ten-inch record is on said turntable but cannot enter said notch when the notched member is depressed by a twelve-inch record whereby to intercept the inward movement of said pickup arm moving means to properly position the pickup arm at the beginning of a twelve-inch record.
